UNITED STATES PATENT OFFICE.

SAMUEL L. WENTZ, OF NEWARK, NEW JERSEY.

BILL-FOLD.

932,205.

Specification of Letters Patent. Patented Aug. 24, 1909.

Application filed August 2, 1907. Serial No. 386,755.

To all whom it may concern:

Be it known that I, SAMUEL L. WENTZ, a citizen of the United States, residing at Newark, in the county of Essex and State of New Jersey, have invented certain new and useful Improvements in Bill-Folds; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to that class of pocket-books known in the art as bill-folds; and, the invention has reference, more particularly, to a novel, simple and neat construction of bill-fold, comprising two main foldable sections or elements, each section being provided with a retaining or holding member, and all being constructed and arranged in such a manner, that a stack of bills can easily be held in their folded relation between the two cover-sections of the bill-fold, without producing an unsightly package.

This invention has for its further object to provide a bill-fold of the general character hereinafter set forth, the same being of such a construction, that any one or more of the bills, can be removed with the least inconvenience, and without being compelled to remove the entire stack of bills from the bill-fold, as has now ordinarily to be done with the various forms of pocket-books or bill-folds at present in use.

Other objects of this invention not at this time more particularly mentioned will be clearly understood from the following detailed description of my present invention.

The invention consists, therefore, in the novel bill-fold hereinafter more fully described; and, furthermore, this invention consists in the various novel arrangements and combinations of parts, as well as in the details of the construction of the same, all of which will be more fully described in the following specification, and then finally embodied in the claim which is appended to and which forms an essential part of this specification.

The invention is clearly illustrated in the accompanying drawings, in which:—

Figure 1 is a face view of a bill-fold, with the foldable sections in their folded or closed

relation, said view illustrating one embodiment of the principles of my present invention; Fig. 2 is an edge view of the same; and Fig. 3 is a plan view of the bill-fold with its foldable sections shown in their open relation, said view showing also the manner of arranging a stack of bills between the two cover-sections of the bill-fold. Fig. 4 is a similar view to that shown in said Fig. 3, with the stack of bills removed, said view showing more particularly the arrangement of a pair of bill-holding or retaining members or elements each one of which is secured along one of the narrower marginal edges of the foldable sections of the bill-fold in a hinge-like manner. Fig. 5 is a cross-section taken on line 5—5 in said Fig. 1, said section being made on an enlarged scale; Fig. 6 is a transverse section taken on line 6—6 in Fig. 4, said section being made on an enlarged scale; and Fig. 7 is a similar section, taken on line 7—7 in said Fig. 4, said view being likewise made on an enlarged scale. Figs. 8 and 9 are two detail plan views of the connecting strap or band by means of which the two main foldable sections of the bill-fold can be secured in their closed relation.

Similar characters of reference are employed in all of the said above described views to indicate corresponding parts.

Referring now to the accompanying drawings, the reference-character 1 indicates the complete bill-fold, the same being made of any soft material, such as leather of the various kinds, so as to produce an ornate article of manufacture of great use, and which is readily carried in the pocket. The main body of the bill-fold comprises two main cover-sections or members 2 and 3 which are integrally connected at 4, so as to be adapted to be folded one upon the other in a hinge-like manner. At their marginal edge-portions, these sections or members 2 and 3 are usually formed with folded or turned over portions 5, and 6 indicates a suitable inner lining made of leather, or any other suitable material.

Suitably secured in a hinge-like manner along one of the narrow edge-portions of the main section or element 2, upon the inner portion of the device, by means of stitches 7, or other suitable fastening means, is a substantially rigid or stiff body, member or element 8, usually made of the same material as the section 2, a facing 9 being preferably arranged and secured upon said body

or member. A leather or other suitable element 10 is secured upon said facing 9, said element 10 being doubled upon itself, as at 11, and the turned over marginal edge-portion 12 being sewed fast to the said main section or element 2 by means of the previously mentioned stitches 7, as will be clearly understood from an inspection of Fig. 6 of the drawings.

10 The space between the element 10 and the doubled-over portion 11 may be provided with a suitable lining, as 13, the various parts being suitably arranged to provide a pocket or receptacle 14 into which may be slipped a card of identification, or the like. 15 Likewise there is secured in a hinge-like manner along the corresponding edge-portion of the other main section or element 3, upon the inner portion of the device, by means of stitches 15, or other suitable fastening means, a substantially rigid or stiff element or body 16, usually made of the same material as the section 3, said element or body 16 being provided with the folded or turned over edge-portions 17 and a facing 18, substantially as shown in said Fig. 7 of the drawings. Owing to the substantially rigid or stiff character of these two holding or retaining elements which are thus fastened along one of their marginal edge-portions to the inner faces of the main body-sections or members of the bill-fold, these elements have spring-like characteristics, so that their normal tendency is to forcibly bind upon the inner faces of the main body-sections of the bill-fold, so that any one or more bills, when arranged between the parts, in the manner illustrated in said Fig. 1 of the drawings, will be securely and 40 positively held in position between the two foldable members or sections 2 and 3 of the bill-fold, whether in their closed or opened relations, as will be clearly understood.

45 As will be noticed more particularly from an inspection of Figs. 5, 6 and 7, the turned over marginal edge-portions of the two main body or cover-sections 2 and 3 are preferably pressed into such shape, that their edges will form flexibly disposed flanges, whereby the parts will assume, when closed upon each other, the relative positions substantially as indicated in Fig. 50 5 of the drawings, according to the thickness of the stack of bills which is held in place between the two foldable sections 2 and 3.

Having thus described the general construction of the bill-fold, I will now briefly describe its use and the manner of placing 60 and removing one or more bills in their secured or held positions between the two foldable main sections and the inner holding or retaining members or elements of the device.

65 After having opened or unfolded the two sections 2 and 3 in the manner shown in said

Fig. 4 of the drawings, the bills 19, either one or more of them, are arranged directly beneath the spring-like holding or retaining members or elements, with about one-third of the length, as 20, of the bill or bills extending beyond the edge-portion of the section 2. Before closing the two sections 2 and 3, the portion 20 of the bill or bills is folded over upon and over the upper face of the holding or retaining member or element which is connected with the section 2, substantially as clearly illustrated in Fig. 3 of the drawings, after which the two main body or cover-sections 2 and 3, with the stack of bills held between them, are folded together in the manner indicated in Figs. 1 and 2 of the drawings, the parts being held together by means of a fastening device 21, or other suitable locking device. This fastening device consists, essentially, of a pair of hollow bands or strap-like sections 22 and 23, made so that the end-portion of one section will slip over or telescope with the other section, an elastic band or webbing 24 being arranged within the tubular or hollow sections 22 and 23. The end-portion of one of said sections, as 22, is suitably fastened to the section 3, the other section, as 23, being provided with any form of catch 25, having the usual head-receiving depression 26, see Figs. 3 and 4, for springing 95 said catch 25 in holding engagement with a suitable button upon the other body or cover-section 2 of the device, said button, however, in this instance not being shown. The use and operation of the strap or band and its 100 holding catch are evident, and need not be further described.

To remove one or more of the bills from the stack, all that is necessary is to unfold the folded-over portion 20 of the said stack, so 105 that the operator can select the bill or bills desired, the bill or bills thereupon being pulled from the stack without in the least disturbing the relative positions of the other bills, which are still held in their place by the 110 previously described holding or retaining members or elements in the manner set forth in the foregoing specification. By slightly raising or lifting said holding or retaining elements or members into their angular positions, substantially as shown in said Figs. 6 and 7 of the drawings, it will be evident, that any one or more bills can be readily placed in position between the foldable sections of the bill-fold, or between or upon a stack of bills 115 120 already held in place.

I am fully aware that some changes may be made in the various arrangements and combinations of parts, as well as in the details of the construction of the same, without departing from the scope of the present invention, as defined in the appended claim. Hence, I do not limit my invention to the exact arrangements and combinations of the various parts as described in the foregoing 130

specification and as illustrated in the accompanying drawings, nor do I confine myself to the exact details of the construction of the said parts.

5 I claim:—
A bill-fold comprising a pair of main foldable sections, said sections being connected in a hinge-like manner and said two sections when in their opened relation being but about 10 two-thirds the length of a bill, the marginal edge-portions of each section being doubled-over and provided with an inwardly extending and flexible marginal flange, so as to provide a receiving depression in each main section, a holding or retaining element arranged 15 in each receiving depression, and means extending along one of the narrower edge-portions of each retaining element consisting of stitches for securing each retaining element

in a hinge-like manner within a receiving depression in each main section, one of said retaining elements being longer than the other element, said longer element being provided with a card-receiving pocket, all arranged that a stack of bills can be placed beneath 20 said retaining elements, with one end-portion of the stack of bills projecting beyond one of the bill-fold sections and the edge of said longer retaining element and adapted to be folded over said element, substantially as 25 30 and for the purposes set forth.

In testimony, that I claim the invention set forth above I have hereunto set my hand this 1st day of August, 1907.

SAMUEL L. WENTZ.
